UNITED STATES PATENT OFFICE.

HENRY E. HARRIS, OF INDIANAPOLIS, INDIANA.

HINGE.

1,277,067.

Specification of Letters Patent. Patented Aug. 27, 1918.

Application filed June 6, 1917. Serial No. 173,124.

To all whom it may concern:

Be it known that I, HENRY E. HARRIS, a citizen of the United States, residing at Indianapolis, in the county of Marion and 5 State of Indiana, have invented certain useful Improvements in Hinges, of which the following is a specification, reference being had therein to the accompanying drawing.

The invention relates to hinges, and more 10 particularly to the class of quick detachable hinges for use on ordinary swinging doors, screen doors or the like.

The primary object of the invention is the provision of a hinge of this character 15 preferably of the spring type wherein it can be readily mounted and detached for the hanging or removal of a door without necessitating removing any screws, pins or the like when the door is to be detached.

Another object of the invention is the provision of a hinge of this character wherein 20 the door can be mounted to swing from the right hand or left hand side of the door frame and is readily detachable with despatch without removing the parts of the 25 hinge from the door or the door frame or the removal of screws, pins or other like fasteners.

A further object of the invention is the 30 provision of a hinge of this character wherein the strength thereof is materially increased to give maximum durability in the use of the hinge and to enable the hanging of the door or its removal with despatch.

A still further object of the invention is 35 the provision of a hinge of this character which is novel in form, possessing simplicity in construction, reliability and efficiency in its operation, and also one which can be 40 manufactured at a minimum expense.

Other objects will be in part obvious and in part hereinafter set forth.

The invention accordingly consists in the 45 features of construction, and the combination of elements and arrangement of parts which will be exemplified in the construction hereinafter described, and the scope of the application of which will be indicated in the appended claim.

In the accompanying drawings:

Figure 1 is a fragmentary side elevation 50 of a door and frame showing applied thereto a hinge construction in accordance with the invention;

Fig. 2 is a sectional view on the line 2—2 of Fig. 1;

Fig. 3 is an elevation showing a portion of the hinge detached from the other part thereof;

Fig. 4 is a perspective view of the other 60 part of the hinge termed the door frame part or keeper.

Similar reference characters indicate corresponding parts throughout the several 65 views of the drawings.

Referring to the drawings in detail, A designates generally a portion of a door which is of the swinging type and B a portion of the door frame of the ordinary construction, the door and door frame being 70 shown to merely illustrate the application and use of the hinge hereinafter fully described. It is to be understood that the hinge is adaptable to various styles of doors of the swinging type, such as the solid panel door, 75 screen door or the like, and said hinge may be of the spring type or any other type.

The hinge comprises the pivotally connected leaf sections 10 and 11 respectively, which are formed with pintle ears 12 for 80 the pintle or pivot 13 swingingly connecting the said sections, the section 10 being of a construction to constitute a housing for the spring 14, which coacts with the section 11 for the tensioning of the hinge in the opening of the door, and this section 10 is fastened to the door A as shown in Fig. 1 of the drawing or in any other desirable manner. The section 10 of the hinge can be otherwise constructed, as the occasion may 85 require, and the spring 14 eliminated.

Mounted upon the door frame B is a part 90 of the hinge which will be termed the keeper, comprising a cleat-like cheek plate 15 which is formed at one edge with a curved 95 flange 16 formed with apertured ears 17, the same being offset with respect to the plane of the cheek plate 15, and passed through these ears are suitable fasteners such as screws 18 which are engaged in the door 100 frame B for the mounting of the keeper thereon. The cheek plate 15 is offset the required distance from the face adjacent thereto of the door frame B so as to accommodate the leaf section 11 which is readily 105 insertible within the keeper and removable therefrom.

The curved extension 16 on the cheek plate 15 is formed to provide an inner retaining channel or groove 19 for the reception of a 110 retaining semi-cylindrical rib 20 formed on the leaf section 11 which, in opposite end

edges, is provided with notches 21 which constitute a seat for accommodating a stop or bearing screw 22 which is adaptable for engagement in either of a pair of openings 5 or holes 23 formed in the cheek plate 15 near opposite ends thereof, the cheek plate being formed on its outer face with a thickened portion 24 for the strengthening thereof to withstand the strains in the use of the hinge.

13. When the door A is hung to swing at the left hand side of the door frame B the keeper is applied or secured in place upon the door frame as shown in Figs. 1 and 2 of the drawing and the stop screw 22 is

15. mounted within the lowermost hole or opening 23 in said cheek plate 15 of the keeper to limit the insertion of the leaf section 11 within said keeper which is passed downwardly between the cheek plate 15 and the

20. face adjacent thereto of the door frame from the upper end of the keeper, and the shoulder or rib 20 engages in the channel or groove 19 so that the leaf section 11 cannot be pulled outwardly in a horizontal direction from the keeper, and when the leaf section 11 is properly engaged therein the top screw 23 is received in the notch 21 in the end adjacent thereto of the leaf section 11, which also prevents the outward pulling of

25. said leaf section from the keeper, and this screw limits the insertion of the leaf section 11 in the keeper. It is readily apparent that the leaf section 11 of the hinge, on slightly opening the door and the lifting thereof, 30 may be removed from the keeper without necessitating the removal of any screws, pins or other fasteners.

Now should it be desired to hang the door for swinging movement at the right hand side of the door frame B the keeper is in-

verted or reversed when mounted on the door frame at the right hand side thereof and the stop screw 22 engaged in the lowermost hole in the cheek plate of the keeper to limit the insertion of the leaf section 11 45 of the hinge when engaged in said keeper.

From the foregoing description, taken in connection with the accompanying drawing, the construction and manner of use of the herein described hinge will be readily apparent and, therefore, a more extended explanation has been omitted.

Having thus described my invention, I claim:

In a hinge, the combination with two pivotally connected leaves, the one having screw holes therein to permit its attachment to a door, the other having a retaining rib formed adjacent to its longitudinal edge and semicircular notches formed in its ends 55 between the retaining rib and its pivotal connection with the first leaf, of a keeper adapted to be mounted upon the frame of said door, the keeper having an internal groove between the retaining rib and being provided with a cheek plate, between which and the door jamb, the second said leaf member is designed to be held, the cheek plate having formed therein, transverse holes positioned one near either end of the cheek plate, and a screw for insertion in either hole of the cheek plate, so that the second said leaf member may be sustained thereby, the screw engaging in one of the notches of said leaf, whereby the hinge and its keeper may be 60 employed on right hand or left hand hung doors to removably support the said door.

In testimony whereof I affix my signature.

HENRY E. HARRIS.

Copies of this patent may be obtained for five cents each, by addressing the "Commissioner of Patents, Washington, D. C."
